CLAIM

The ornamental design for a T type nail, as shown and described.

DESCRIPTION

FIG. 1 is a perspective view of a T type nail showing my design;

FIG. 2 is a front elevational view therefore, the rear elevational view being the mirror image thereof;

FIG. 3 is a left side elevational view thereof, the right side elevational view being the mirror image thereof;

FIG. 4 is a top plan view thereof;

FIG. 5 is a bottom plan view thereof; and,

FIG. 6 is a perspective view of a T type nail in use.

The broken lines shown on the drawings are for illustrative purposes only and form no part of the claimed design.
